CLAIM

The ornamental design for a livestock vaccination cooler, as shown and described.

DESCRIPTION

FIG. 1 is a top front perspective view of a livestock vaccination cooler showing my new design;
 FIG. 2 is a front elevation view thereof;
 FIG. 3 is a rear elevation view thereof;
 FIG. 4 is a top plan view thereof;
 FIG. 5 is a bottom plan view thereof;
 FIG. 6 is a right elevation view thereof;
 FIG. 7 is a left elevation view thereof; and,
 FIG. 8 is a top front perspective view thereof, shown with lid open.

The broken lines shown in the drawings illustrate portions of the livestock vaccination cooler that form no part of the claimed design.
